(No Model.)

W. H. HOAG.
COVERING FOR FIRE DOOR OPENINGS.

No. 484,636.

Patented Oct. 18, 1892.

WITNESSES:

John W. Fisher *Fig. 7.*
Grace T. Many. *Fig. 1.*

UNITED STATES PATENT OFFICE.

WILLIAM H. HOAG, OF AMSTERDAM, NEW YORK.

COVERING FOR FIRE-DOOR OPENINGS.

SPECIFICATION forming part of Letters Patent No. 484,636, dated October 18, 1892.

Application filed April 18, 1892. Serial No. 429,547. (No model.)

To all whom it may concern:

Be it known that I, WILLIAM H. HOAG, a citizen of the United States, residing at the city of Amsterdam, county of Montgomery, State 5 of New York, have invented a new and useful Improvement in Covering for Fire-Door Openings, of which the following is a specification.

My invention relates to improvements in 10 the construction of the top of the fire-door opening in a steam-boiler furnace and in the rear of the boiler over the flues; and the object of my invention is to provide a means for holding a refractory substance in position 15 over the fire-door opening and which may be adjusted and parts thereof removed when desired. I accomplish this object by means of the mechanism illustrated in the accompanying drawings, in which—

20 Figure 1 is a front elevation of a furnace provided with my invention. Fig. 2 is a longitudinal section through a steam-boiler furnace. Fig. 3 is a plan of the frame. Fig. 4 is a section along the lines 1 1 on Fig. 3. Fig. 25 5 is a section along the lines 2 2 on Fig. 3. Fig. 6 is a plan along the lines 3 3 on Fig. 4. Fig. 7 is a plan through the air-chamber, and Fig. 8 is an end view of the plate placed in the form of an arch.

30 Similar letters refer to similar parts throughout the several views.

I construct a frame A, which is composed of a series of cross-shaped metallic plates A', secured together by bolts B B, passing through 35 ties b b, extending across the adjoining ends of each of the arms of said cross-shaped plates and also through the ends of the plates. The ends of the adjoining cross-shaped plates A' are secured by means of bolts C C, passing 40 through the sides thereof and through corresponding ties c. Thus I arrange a number of plates A' A' together in such a manner as to leave openings A² A² at frequent intervals and place a sufficient number of the plates 45 together to form a covering for the fire-door opening in a steam-boiler furnace.

In contact with the masonry above the fire-door opening I place the metallic plate E, which is supported by the standards e e, resting 50 upon the frame A. Extending across the frame A, I place a series of bars F, resting upon the frame, to which I secure by hooks f,

passing through the openings A² A² into the frame, the anchor-frame H. The anchor-frame H is thus suspended below the frame 55 A throughout its whole extent, and at its end toward the interior of the furnace it projects upwardly to a point slightly above the frame A, as shown in Figs. 2 and 4. The anchor-frame H is provided with slots h, within which 60 the anchors G are adjustably secured. The lower edge of the slots h are provided with notches h'. At the end of each of the slots h, nearest the center of the anchor-frame H, is formed a square opening h². In the slots h I 65 place the anchor G. The anchor G is provided with a shank g, upon which are placed two lugs g', slightly separated from each other, the shank g between the two lugs g' passing into the slot h at the squared opening h², the opening h² being large enough to admit of the passage of the lug g'. The anchor G is then moved through the slot h until it reaches the notch h', in which it is desired to locate the anchor. Then the 75 anchor is turned, bringing the narrower side of the shank into the notch h', where it fits snugly and is held securely in position, one of the lugs g' being on one side of the anchor-frame, the other of the lugs g' on the opposite 80 side of the anchor-frame, the shank g between the two lugs fitting securely within the notch h' of the slot h. The arms of the anchor are usually constructed in the form shown in Fig. 5, being arranged in the form of an open 85 square, the side opposite the shank being broken, leaving a space between the adjoining ends. Extending from one arm to the other of the anchor I place the narrow ties g².

As a covering for the ends of the anchor-frame H, I place the finishing-plate J, extending across from one side of the fire-door opening to the other. The anchors G are placed alternately one on each side of the frames H, as shown in Fig. 6, except on one side of the 95 sections, where the anchors are made double, one on each side of the frame, and a sufficient number of the frames are placed in position over the fire-door opening, as may be desired.

For the purpose of securing the anchor-frames together I place the bolts K K, extending through the series of frames from one end to the other, by means of which the frames may be drawn toward each other. Along the 100

edge of the air-chamber M, which is the space between the plate E and the frame A and which separates the interior of the furnace from said air-chamber, I place the plate L, which is provided with an opening about midway between its ends, communicating with a channel m^2 through the cement at the end of the anchor-frame H, which in turn communicates upon each side of the interior of the furnace.

In order that the air may be caused to circulate through the chamber M, a space m is constructed in the fire-walls on each side of the fire-door opening which communicates beneath the dead-plate in the furnace at one end and with the air-chamber M between the plate E and the frame A at the other end, and a draft will be maintained from below the dead-plate, up through the air-chamber, out through the opening in the plate L and channel m^2 of the interior of the furnace. The cement or other refractory substance, it is understood, is placed in contact with the frame A and the anchors G and occupies the position shown by dotted lines in Fig. 4, and after it is hardened into a homogeneous body it is retained in position by means of the anchors which are embedded within the substance. When the fire-door opening is in the form of an arch, Fig. 8 shows the position of the end of the cement-carrying frame. I do not limit myself, however, to the exact arrangement of the opening communicating with the air-chamber, since, instead of communicating with the space below the dead-plate, it may open through the side walls of the furnace or in any suitable place.

The cement or other refractory heat-resisting substance is put on a single section of my anchors or cement-carriers, subjected to a very powerful heat, caused to solidify and forming a fire-briek, and then the section containing the cement or other refractory substance thus solidified is suspended from the frame by means of the hooks already described after the frame is placed in position about the fire-door opening. When a section or portion thereof becomes broken or burned out, it may be removed and a new section having the cement hardened upon it may be substituted therefor without removing the main plate. Thus is avoided the necessity of placing a mass of green cement in contact with the old and hardened cement for the purpose of repairing a defect or injury. This is one of the principal advantages of my invention, it being almost impossible to repair the covering of the fire-door opening, when an injury has occurred to it, by placing green cement in contact with the old and hardened substance and have it retain its position without leaving cracks and openings when it becomes hardened.

65 By my method an injured section may be replaced by a section of hardened cement and the small opening at the line of connection

may be filled with green cement, or by placing the anchors on each side of the anchor-frame, as shown in the extreme right of Fig. 70 5, or when the modified form is used by having one overlap the other.

For the purpose of removing a section it is necessary to be able to reach the upper surface of the frame A within the air-chamber 75 M. In order to remove the hooks f from the plate F, I arrange the plate L, extending across the rear of the air-chamber M, which is cemented in position and which may be removed by cutting away the coating of cement 80 along the outer side, which will give a free access to the chamber and permit a removal of the section.

One of the advantages of my invention is that the frame may be formed to cover fire-door openings differing in size, whether the opening is in a horizontal plane or in the form of an arch, without making a separate frame for each individual furnace where these differences occur, since by means of a tenon in 90 the cross-plates A' these plates may be drawn closer or removed farther from each other, or it may be removed, as desired, thus providing for the differing sizes and contours of the covering in a fire-door opening.

What I claim as my invention, and desire to secure by Letters Patent, is—

1. A frame for supporting cement-holding anchors, composed of a series of plates adjustably secured together, provided with apertures between said plates, a series of bars extending across said plates from one end to the other thereof, and a series of anchor-holding frames suspended from said bars by means of suitable hooks, substantially as described, and for the purpose set forth.

2. In an apparatus for retaining fire-resisting substance above the fire-door opening of a furnace, consisting of a plate in contact with the top of said opening, a frame beneath said plate and separated therefrom, an air-chamber between said frame and said plate, said air-chamber communicating with the interior of said furnace, communication between said air-chamber in the outside of said furnace, 115 with a series of adjustable sections suspended from the lower one of said frames carrying a heat-resisting substance, substantially as described, and for the purpose set forth.

3. In an apparatus for covering the fire-door opening of a furnace, an air-chamber communicating with the outside of the furnace, provided with a plate between the interior of the furnace and said chamber capable of being removed from the interior of the furnace, the bottom of said air-chamber having a frame supporting adjustable sections of cement-carriers, substantially as described, and for the purpose set forth.

4. An apparatus for covering the fire-door opening of a furnace, consisting of an anchor-holding frame provided with a longitudinal slot through its side, said slot having near the center of said anchor-holding frame a squared

opening, said frame suspended by means of suitable hooks from a frame placed across said fire-door opening, and an anchor provided with a shank upon which two lugs are placed slightly separated from each other, the shank between the said lugs fitting snugly within said longitudinal slot, one of these lugs being upon either side of said anchor-holding frame, said anchor provided with outwardly-projecting arms separated from each other, said anchors embedded in the fire-resisting substance, substantially as described, and for the purpose set forth.

5. An apparatus for covering the fire-door opening of a furnace, composed of a series of

adjustable sections of anchor-holding frames suspended from a horizontal frame placed across said fire-door opening, in combination with a series of bolts passing through said sections from one side of the opening to the other, by the operation of which said anchor-holding frames may be drawn toward each other, with an air-chamber placed above said suspending-frame communicating with the interior of said furnace, substantially as described, and for the purpose set forth.

20 25 WILLIAM H. HOAG.
